UNITED STATES PATENT OFFICE.

MAX BREMER, OF NEW BEDFORD, MASSACHUSETTS.

DESIGN FOR A CASKET-PLATE.

SPECIFICATION forming part of Design No. 25,096, dated January 28, 1896.

Application filed December 2, 1895. Serial No. 570,860. Term of patent 7 years.

To all whom it may concern:

Be it known that I, MAX BREMER, a citizen of the United States, residing at New Bedford, in the county of Bristol and State of Massachusetts, have invented and produced a new and original Design for a Casket-Plate, of which the following is a specification, reference being had to the accompanying drawings, in which—

Figure 1 is a top plan view, and Fig. 2 a side elevation, of a casket name-plate, showing my new design. Fig. 3 is a top plan view, and Fig. 4 a side elevation, of a casket-ear, showing this same design.

The leading feature of my new design consists in the contour or configuration of the plate, which contour consists in the curved margin fluted vertically relatively to the base and followed by a rising transverse swell, which is followed in turn by a transversely-ribbed space next a wide reverse scroll, which is followed by a curved margin that is fluted vertically in relation to the base, the two

fluted margins being at opposite sides of the plate.

In the drawings, A is a curved margin vertically fluted relatively to the base, and B is the rising transverse swell which follows margin A.

C represents the ribbed space next swell B and D, which is the wide reverse scroll, following which is a curved margin A' fluted like margin A. This contour or configuration constitutes the leading and distinguishing feature of my design.

What I claim is—

The herein-described design for a casket-plate substantially as set forth.

In testimony whereof I have signed my name to this specification, in the presence of two subscribing witnesses, on this 19th day of October, A. D. 1895.

MAX BREMER.

Witnesses:

F. E. LANSING,
H. A. MCPHERSON.
